UNITED STATES PATENT OFFICE

JESSE E. MATTER, OF WILKINSBURG, PENNSYLVANIA, ASSIGNOR TO WESTINGHOUSE ELECTRIC & MANUFACTURING COMPANY, A CORPORATION OF PENNSYLVANIA

INSULATOR

Application filed July 15, 1927. Serial No. 205,877.

My invention relates to insulators and particularly to insulators for mounting overhead trolley conductors in tunnels and similar places of limited head room.

One object of my invention is to provide an insulator of the above-indicated character, that shall employ its dielectric material to maximum advantage and have substantially a maximum amount of the material for an insulator of height given to conserve head-room.

Another object of my invention is to provide a tunnel insulator of inverted substantially frusto-conical shape that shall be rigidly supported at its upper or major-base end, proof against the admission of moisture thereto from above and have moisture-shedding surface-creepage flanges constructed in accordance with the voltage gradient thereof.

Another object of my invention is to provide an overhead insulator in which the dielectric material shall extend substantially throughout the length thereof and have metal terminals disposed substantially within the longitudinal limits defined by the dielectric structure.

Another object of my invention is to provide an insulator including a dielectric portion of hollow substantially frusto-conical shape that shall embody a transverse wall serving the combined functions of closure means therefore and means for bracing the same against cantilever loads.

Another object of my invention is to provide an overhead conductor-supporting tunnel insulator of hollow inverted substantially frusto-conical shape that shall have imperforate sides and be transversely closed adjacent to its upper end and that shall have breathing means adjacent to its lower end.

Another object of my invention is to provide an insulator that shall be simple and durable in construction, economical to manufacture and effective in its operation.

In tunnels and similar locations, having limited overall height or overhead room, it is difficult to provide an overhead trolley conductor supporting insulator that is sufficiently strong and permanent in char-

acter, proof against the damaging effects of condensed moisture, sufficiently resistant to the relatively high voltages employed and that has other features tending to render it a generally satisfactory device.

It is my aim to overcome the objections attending the use of tunnel insulators heretofore employed and that shall have other advantages thereover.

Accordingly, in practicing my invention I provide an insulator embodying a dielectric member of hollow inverted substantially frusto-conical shape having imperforate longitudinal-side and transverse walls, side flanges, terminal means and other features that are so constructed and related as to attain all of the objects of my invention.

Figure 1 of the accompanying drawings is a top plan view of an insulator constructed in accordance with my invention, and

Fig. 2 is a longitudinal side view thereof, partially in section, and partially in elevation.

A dielectric body member 2 of substantially frusto-conical shape embodies side walls 3, a transverse wall 4, cylindrical end terminal receiving portions 6 and 7 and a plurality of longitudinally spaced annular surface-creepage flanges 9.

The member 2 is preferably constructed of porcelain with the walls 3 and 4 thereof of substantially the same thickness to provide uniform strength and density of texture.

The member 2 has transverse substantially parallel-plane end surfaces 11 and 12 disposed substantially at the outer limits of the structure as a unit.

Since the structure is to be rigidly mounted with its upper or major base end adjacent to the tunnel roof, the wall 4 is disposed slightly inwardly from the surface 11 to better permit the insulator to be disposed level against its upper supporting means than might be the case with the upper surface of the wall 4 flush with the surface 11.

In contradistinction to frusto-conical insulators that are usually disposed with the major bases at the lower ends thereof and surface creepage flanges sloping downwardly toward the major bases, the flanges 9 of the

device of my invention are preferably provided with upper rain shedding surfaces sloping downwardly and outwardly relative to the major base. These flanges are also, 5 preferably of downwardly successively decreasing diameters and increasing lateral extent from the wall portion 3, more nearly in accordance with the voltage gradient of the insulator which is stronger at the lower or 10 live end of the structure and not uniformly distributed between its ends. The flanges may also, be of varying shapes and spaced varying distances relative to each other, in accordance with the gradient drop adjacent 15 to the individual flanges.

An upper terminal member 14 comprises a cylindrical or ring portion 15 that is secured, as by a body of cement 16, to the cylindrical portion 6 and has holding portions 17 extending laterally substantially in the plane of the surface 11. The portions 17 may be in the form of hooks permitting the insulator, as a unit, to be mounted temporarily in operative position, by turning the insulator about its longitudinal axis to place the hook portions 17 over the heads of depending bolts which may be subsequently tightened against the portions 17.

A lower terminal member 19 is provided 30 with a cylindrical portion 20 for attachment, as by a body of cement 21, to the lower cylindrical portion 7 of the body 2, a relatively thin transverse wall portion 22 and laterally extending apertured holding portions 23 for 35 mounting a trolley-conductor clamp or other device thereon.

The wall portion 22 may be provided with one or more openings 25 providing breathing means and to prevent the accumulation of 40 condensed moisture within the body 2.

The wall portion 22 is also, preferably relatively thin to conserve the overall length of the structure and sufficiently strong to provide bracing means against the end surface 45 12.

By my invention, substantially a maximum amount of the dielectric material for a given 50 length is employed and utilized to maximum advantage, a structure of relatively great strength and durability is obtained and an insulator is provided for the particular purposes specified that is an improvement, in general, over insulators for similar purposes heretofore employed.

While I have shown and described a particular 55 form of my invention, changes may be effected therein without departing from the spirit and scope thereof, as set forth in the appended claims.

I claim as my invention:

1. An insulator comprising a hollow dielectric body of inverted substantially frustoconical shape having an imperforate transverse wall adjacent to its upper major-base 65 and cylindrical ends and a plurality of an-

nular side flanges of downwardly successively decreasing diameters and increasing extent from the body, and upper and lower terminals having cylindrical portions secured to said ends and laterally extending portions for 70 mounting the insulator and attaching a conductor to the same, respectively, said terminals having transverse-plane outermost mounting surfaces substantially parallel, and closely adjacent, to the planes of the ends of 75 said dielectric body.

2. An insulator comprising a hollow dielectric body of inverted substantially frustoconical shape having a wall closing its upper end, cylindrical ends and a plurality of anular side flanges of downwardly successively decreasing diameters and increasing extent from the body, an upper ring terminal having portions for mounting the insulator, and a lower terminal having a cylindrical portion 80 secured to said body, an apertured transverse end wall and laterally-extending conductor-mounting portions.

3. An insulator comprising a hollow dielectric body of inverted substantially frustoconical shape having an inwardly offset wall closing its upper end, cylindrical ends and a plurality of downwardly - and - outwardly sloping annular side flanges of downwardly successively decreasing diameters and increasing extent from the body, an upper ring terminal having portions for mounting the insulator by turning the same, and a lower terminal having a cylindrical portion secured to said body, an apertured transverse end wall and laterally-extending conductor-mounting portions.

In testimony whereof, I have hereunto subscribed my name this 7th day of July, 1927.

JESSE E. MATEER.
